UNITED STATES PATENT OFFICE

HOWARD D. COLMAN, OF ROCKFORD, ILLINOIS, ASSIGNEE, BY MESNE ASSIGNMENTS, TO BARBER-COLMAN COMPANY, OF ROCKFORD, ILLINOIS, A CORPORATION OF ILLINOIS.

BOBBIN AND YARN PACKAGE.

Application filed May 17, 1918, Serial No. 235,071. Renewed September 18, 1920. Serial No. 410,010.

To all whom it may concern:

Be it known that I, HOWARD D. COLMAN, a citizen of the United States, residing at Rockford, in the county of Winnebago and State of Illinois, have invented certain new and useful Improvements in Bobbins and Yarn Packages, of which the following is a specification.

One of the objects of this invention is to produce a yarn package especially adapted to facilitate the doffing operation and arranged for use in apparatus (as, for example, a weft-replenishing loom) wherein the end of the thread of the package is to be mechanically found.

Another object of the invention is to provide a bobbin especially adapted for the mechanical finding of the thread-end.

In the accompanying drawings, Figure 1 is an elevation of a bobbin and yarn package embodying the features of my invention. Fig. 2 is a longitudinal central section. Fig. 3 is a view taken from the tip end of the bobbin. Fig. 4 is a fragmental view of the tip of the bobbin upon an enlarged scale.

The embodiment herein shown of the invention comprises a bobbin partaking of the general form of a standard weft or filling bobbin and comprising a butt 1 and an upwardly tapering body or barrel 2 terminating in a tip 3. The bobbin may be constructed of wood, as usual. A rounded shoulder or annular surface 4 is provided at the junction of the butt 1 and the body 2.

35 The tip 3 is provided with a suitable number of longitudinal grooves or flutings 5 which terminate upon the tapered end 6 of the tip. Preferably the grooves 5 are formed in the periphery of a metallic sleeve 7.

40 The periphery of the sleeve, i. e., that portion upon which the end-finder coil is to be wound, is tapered slightly toward its outer end (as shown in Fig. 4), for a purpose to appear hereinafter. While various

45 constructions may be used, the wooden body is herein shown as having a cylindrical end 8 of reduced diameter forming an annular shoulder 9. The diameter of the shoulder 9 is the same as that of the inner end of the

50 sleeve 7. The inner end of the sleeve is counterbored to form an annular tapering surface 10. The grooves 5 extend to the extreme inner end of the sleeve and thereby produce a series of points 11 which embed themselves in the shoulder 9 when the sleeve

7 is forced in place, thus leaving no exposed points or projections on which the yarn might catch.

In forming my improved package, a supply yarn mass *a* of the standard or any suitable form is wound upon the body 2 of the bobbin. A small mass of yarn *b* is then wound upon the grooved portion of the tip 3 at a substantial distance from the yarn mass *a*, the grooves 5 extending beneath the mass *b*. Said mass *b* is connected to the yarn mass *a* by means of a strand *c*. A few turns of yarn *e* are then wound upon the bobbin upon or adjacent to the lower end of the yarn mass *a*. To distinguish the coil *e* from the yarn mass *a*, the former is indicated by heavy lines in Fig. 1. The coil *e* is connected to the coil *b* by means of a strand *d*. As will be understood, when the bobbin is in place on the spindle of the spinning machine, the strand *f* extends from the front drawing roll, through the traveler, to the coil *e*. The yarn *e* is of such length that when the bobbin is lifted off the spindle, all, or substantially all, of the coil *e* will slip off the shoulder 4 and become wrapped around the spindle. When an empty bobbin is placed upon the spindle, said wraps of yarn *e* become clamped between the spindle and the empty bobbin, whereupon the operator completes the operation of doffing the full bobbin by pulling the bobbin away from the spindle, thus breaking the strand *d*.

When the bobbin has been placed in the apparatus wherein the end of the thread is to be found, as, for example, a loom, the coil or yarn mass *b* is stripped off the tip 3 by suitable means such as a hook or cluster of hooks (not shown). Said hooks approach the yarn mass *b* by movement longitudinally of the bobbin tip and yield laterally to pass over said yarn mass. The reason for slightly tapering the portion of the sleeve 7 on which the yarn mass *b* is wound is to prevent said yarn mass from being pushed toward the yarn mass *a* by the hooks. When the direction of movement of the hooks is reversed, the yarn mass *b* is drawn off the tip 3, the points of the hooks traveling through the grooves 5 and thus obtaining an effective hold upon the yarn mass *b*. As the yarn mass *b* is drawn off the tip 3, it is followed by the strand *c* constituting the found end and also by the strand *d*. Inasmuch as the

yarn at *e* was practically only sufficient to serve the purpose of connecting the yarn to the empty bobbin, there is substantially no yarn *e* remaining upon the bobbin to unwind in the end-finding operation. If an excessive amount of yarn *e* were wound upon the bobbin, the strand *c* in unwinding under the strand *d* might break. If the strand *d* broke, the remnant of yarn *e* would either 10 break the weft thread or be woven into the cloth. If neither of the strands *c* and *d* broke, there would be formed a strand of greater or less length (*d* plus *e*) which would trail along with the found end *c*. If this 15 strand were of excessive length it would reach into the cloth and cause a defect therein.

While the invention has been herein disclosed in connection with a filling bobbin, 20 it will be understood that the invention is not limited thereto, but may be embodied in a warp bobbin, and that the package herein shown may be advantageously employed in other textile apparatus than looms.

25 I claim as my invention:

1. A bobbin having, in combination, a body having a reduced upper end-portion forming an annular shoulder, and a metallic sleeve fitting tightly upon said reduced end-portion, the inner end of said sleeve being counterbored, said sleeve having a peripheral series of longitudinal grooves extending to the counterbored end of the sleeve, whereby 30 a series of points are produced upon the inner end of the sleeve, said points being embedded in the bobbin body.

2. A bobbin having, in combination, a body having a reduced upper end forming a shoulder and a metallic sleeve fitting tightly 40 upon said reduced end and abutting said shoulder, said sleeve being provided with a peripheral series of longitudinal grooves and the upper end of the sleeve being tapered.

45 3. A bobbin having, in combination, a body and a metallic tip, the yarn-receiving portion of said tip being longitudinally grooved and being slightly tapered toward its outer end.

50 4. A bobbin having, in combination, a body and a tip, the yarn-receiving portion of said tip being longitudinally grooved and slightly tapered toward its outer end.

5. A bobbin, having, in combination, a body adapted to carry a yarn mass and a tip adapted to carry a coil of yarn, said tip having a peripheral series of longitudinal grooves adapted to extend under such coil.

6. A yarn package consisting of a carrier, 60 a supply yarn mass on the carrier, an end-finder coil on one end of the carrier at a substantial distance from said yarn mass, a strand connecting said yarn mass and coil, a doffing yarn coil on the other end of the carrier, said doffing yarn coil being properly proportioned with reference to the doffing operation, and a strand connecting the end-finder coil to the doffing yarn coil.

7. A bobbin having, in combination, a 70 wooden body having a reduced cylindrical upper end-portion forming an annular shoulder, and a metallic sleeve driven tightly upon said reduced end-portion, and extending to said shoulder, said sleeve having a peripheral 75 series of longitudinal grooves.

8. A bobbin having, in combination, a body having a reduced cylindrical upper end-portion, and a metallic sleeve driven 80 upon said reduced end-portion, said sleeve having a peripheral series of longitudinal grooves.

9. A bobbin having, in combination, a wooden body having a reduced cylindrical upper end forming a shoulder and a metallic sleeve driven tightly upon said reduced end and abutting said shoulder, said sleeve being provided with a peripheral series of longitudinal grooves.

10. A bobbin having, in combination, a body having a reduced cylindrical upper end forming a shoulder and a metallic sleeve driven tightly upon said reduced end and abutting said shoulder.

11. A bobbin having, in combination, a body and a metallic tip adapted to carry an end finder coil, the yarn receiving portion of said tip being longitudinally grooved.

12. A bobbin having, in combination, a body and a tip adapted to carry an end 100 finder coil, said tip having a peripheral series of longitudinal grooves.

In testimony whereof, I have hereunto set my hand.

HOWARD D. COLMAN.
